US0D1099719S

(12) **United States Design Patent** (10) Patent No.: **US D1,099,719 S**
(45) Date of Patent: ** Oct. 28, 2025

(54) **HUMAN BODY DETECTOR**

(71) Applicant: **OPTEX CO., LTD.**, Shiga (JP)

(72) Inventors: **Shun Onishi**, Otsu (JP); **Michinori Noguchi**, Otsu (JP); **Atsuko Sasaki**, Otsu (JP); **Hiroyuki Tomooka**, Otsu (JP); **Takeo Hyodo**, Tokyo (JP); **Tomoyuki Ohba**, Tokyo (JP)

(73) Assignee: **OPTEX CO., LTD.**, Shiga (JP)

(**) Term: **15 Years**

(21) Appl. No.: **29/997,752**

(22) Filed: **Apr. 9, 2025**

(57) **CLAIM**

The ornamental design for a human body detector as shown and described.

DESCRIPTION

FIG. 1 is a first perspective view of front, left and bottom side of a human body detector showing a second embodiment of our new design;

FIG. 2 is a second perspective view of rear, left and top side thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front view showing an energized state thereof.

(Continued)

The broken lines in the figures are included for the purpose of illustrating portions of the human body detector that form no part of the claimed design.

1 Claim, 5 Drawing Sheets
